EMBALMING FLUID CONTROL APPARATUS

Jay H. Metcalf, Grand Rapids, Mich.

Application April 25, 1932, Serial No. 607,277

2 Claims. (Cl. 27—24)

This invention relates to embalming and is more particularly concerned with an embalming fluid control apparatus whereby a body may be completely permeated with embalming fluid without breaking down of tissues or swellings, puffings and the like liable to occur in many cases where the pressure of the embalming fluid is too great. It is a primary object and purpose of the present invention to provide a gauged control of pressure for the embalming fluid and to secure its rise or elevation to the highest points of the body, eliminating guessing as to the amount of pressure which should be used, and rendering the operation sure and perfect in the results attained and eliminating the necessity of the exercise of high skill in the operation which has been more or less requisite on the part of the embalmer heretofore.

60

An understanding of the invention may be had from the following description taken in connection with the accompanying drawings, in which.

65

Fig. 1 is a side elevation of the apparatus of my invention and illustrating the manner in which it is used.

70

Fig. 2 is an enlarged vertical section through the gauged pressure control apparatus.

75

Fig. 3 is a horizontal section substantially on the plane of line 3—3 of Fig. 2.

80

Fig. 4 is a side elevation of the apparatus shown in Fig. 2.

85

Fig. 5 is a central longitudinal vertical section through a detail of the construction used, and

90

Fig. 6 is a somewhat diagrammatic outline of the principle used in forcing the embalming fluid to all parts and particularly the higher parts of the body.

95

Like reference characters refer to like parts in the different figures of the drawings.

100

In the operation of embalming, the body is placed upon a horizontal table 1 face upward, an outline of the body being indicated in dotted lines at 2 in Fig. 1. The embalming fluid may be either pumped under pressure, or the pressure may be gravity induced, the fluid being contained in a jar or other container 3 at an elevation higher than the body so as to provide a pressure head. The fluid flows from the container 3 outwardly through a conduit 4 to the pressure control apparatus forming a part of the present invention.

105

In the construction of the apparatus a supporting plate 5 having a flat under face is provided which may be placed horizontally on the upper side of the table 1. Integral with the

plate 5 is an upwardly extending housing 6 on which rests a ring 7 having an annular flange 8 around it. The ring 7 is formed with a cross connecting bar 9 having a central opening through which a vertical stem 10 passes, the upper end of which is provided with a disc-like head 11, the upper side of which is in a horizontal plane. The lower end of the stem 10 rests upon a leaf spring arm 12, near the free end thereof, the opposite end of which is permanently secured to a lever 13 pivotally connected at its upper end to the bar 9, which has an opening through it for receiving the upper end of the lever. The lever 13 depends from the bar and at its outer side engages against the inner end of an adjusting screw 14 threaded through a side of the housing 6.

A flexible diaphragm 15, which may be of rubber, rubberized silk or other fabric or any other suitable material capable of resisting the action of embalming fluid, is seated in the ring 7 inside the annular flange 8 and is clamped in place by the engagement of the lower end of a cylinder 16 bearing against it and inserted into place inside of the annular flange 8. The upper end of the cylinder is received at the inner sides of a second annular flange 17 extending downwardly from a cover member 18. The parts are all bound together tightly so as to make them liquid and air tight, binding rods 19 passing through lugs projecting outwardly from the cover 18 and from the housing member 6, as best shown in Fig. 4.

This construction provides a chamber above the diaphragm 15 into which the embalming fluid is first entered from the container 3; or from a pump if a pump is used instead of a gravity container. While I have described a specific construction for connecting and holding together the cover 18, the cylinder 16, ring 7 and lower housing member 6, it is evident that many variations in specific detail may be had. For instance the cylinder 16 may be integral with the cover 18 and the ring member 7 integral with the upper end of the housing 6 and a connection made between the parts by means of short bolts rather than the longer rods 19. All of such variations in construction are equivalent and are comprehended by my invention.

The cover 18 at its upper side has an outwardly extending nipple 20, to which the free end of the outlet hose 4 from the container 3 is secured. This nipple is extended integrally with the cover substantially to its center and there is a continuous passage 21 through the nipple and to

the center of the cover where it joins with a vertical passage extending downwardly in and through a downwardly extending sleeve 22 which has openings in its sides as shown. A valve rod 5 23 is mounted for free vertical movement through the lower end of the sleeve 22, which serves as a guide therefor, the lower end of the rod 23 carrying a head 24 having a flat underside which bears upon the upper side of the diaphragm 15 10 directly over the disc head 11 previously described. The upper end of the rod 23 carries a conical valve 25 which in its lower position seats against a complementary valve seat to completely stop the passage of the embalming fluid 15 from the passage 21 downwardly into the chamber surrounded by the cylinder 16. For assembly and inspection and repair purposes the cover directly over the valve 25 is interiorly bored and threaded and is tightly closed by a screw and 20 packing 26.

The outlet from the chamber surrounded by the cylinder 16 is through a depending integral outlet pipe 27 cast with the cover, which has a vertical passage therethrough which turns horizontally in the plane of the passage 21 and extends through an outlet nipple 28 to which an outlet flexible hose conduit 29 is permanently secured. At the free end of the hose 29 a tubular metal needle 30, having an axial passage there- 30 through, is permanently secured.

The base 5 of the apparatus also serves to carry and support a vertical rod 31 which may be detachably connected at its lower end to the base as by screw threading. On the upper end of the 35 rod a member is adjustably secured. Said member comprises a laterally extending lug 32 having a vertical opening therethrough, for passing the rod 31, and with a set screw 33 threaded into the outer end of the lug to bind the rod 40 against said member to hold it in any position to which adjusted in the vertical length of the rod. From the lug 32 a hollow member 34 projects one end of which has an integral longitudinally 45 extending nipple 35 with a passage therethrough communicating with the interior of the member 34. Into the other end of the member 34 a nipple 36 is inserted its inner portion 37 being housed within the member 34 and extending nearly to the opposite end of said member. The nipple 50 36 and its extension 37 have a continuous axial passage therethrough; and in the upper side of the member 34 an air vent opening 38 is made.

A flexible hose 39 is connected at one end to the nipple 36 and at its outer end carries a second tubular needle 40 similar to the needle 30 previously described. A hose 41 is connected at one end to the nipple 35, its other end being free of any connection to other devices or instruments.

60 The cover 18 has an upwardly extending boss 42 connected with which is a gauge 43, there being a free passage through the boss 42 whereby the pressure of the embalming fluid within the cylinder 16 is registered on the gauge to inform 65 the operator of the working pressure of the embalming fluid. A similar gauge 53 connects with the passage 21 to indicate the pressure therein.

In the process of embalming, one part of the body is selected where a vein and artery approach the surface of the body and this ordinarily is in an arm near the armpit. The vein and the artery, which lie alongside of each other, are lifted to the surface and the needle 30 inserted in the artery while the needle 40 is inserted in 75 the vein.

The embalming fluid, passing from the container 3, passes outwardly through the hose 4 and through the passage 21 into the chamber above the diaphragm 15 and will continue to pass the valve 25 until its pressure is great enough to overcome the spring leaf at 12 whereupon the valve 25 will lower to its seat and shut off any further flow of liquid until the pressure within the cylinder 16 is too light to resist the return movement of the spring 12. The extent of opening the valve 25 and the extent of pressure required to close the valve 25 may be regulated by the screw 14 which, when turned inwardly, lifts the spring 12 and requires a greater force of pressure to overcome the same to move the valve 25 to closed position. The pressure within the cylinder 16 is registered by the gauge 43 and informs the operator what the pressure may be. The outward flow of the embalming fluid through the outlet 27, nipple 28 and hose 29 passes through the tubular needle 30 into the artery. The pressure required to cause the embalming fluid to permeate the body depends upon the condition of the body, how long it has been deceased and the like, but in any event the embalming fluid in all cases thins the blood in the arteries and veins, liquefies any clots or coagulation and, by reason of the pressure in the artery of the embalming fluid, the blood is driven from the body at the point where the vein is punctured through the outlet needle 40, the hose 39, nipple 36 and its extension 37 thence through the nipple 35 and the outlet hose 41.

The elevation of the member 34 is as high as the highest point of the body above the table 1. This causes the embalming fluid to permeate all parts of the body and there is no danger of cutting across through capillaries from arteries to veins through the lower parts of the body only, as would be the case if the outlet hose 41 had no higher elevation than the outlet 44 shown in dotted lines in Fig. 6. But by reason of the elevation through which the outgoing fluid must pass to a point as high or higher than the highest points of the body, even though there may be breaking through from arteries to vein through capillaries at times, the pressure of the fluid raised as it is to the elevation of the part 34, causes a complete and thorough permeation of the body by the embalming fluid. In Fig. 6 there has been roughly diagrammed the action which would occur through a cutting across from arteries to veins at the lower part of the body if there was no head of liquid to which it had to be raised and if the outlet was as shown in dotted lines at 44. By elevating the part 34 to cause the blood and other fluids passing from the body to reach such elevation thorough permeation is insured. The vent at 38 permits the entrance of air and destroys any siphoning action which might otherwise take place.

The construction described is very practical and serviceable for the purpose for which it has been designed. The working pressure within the cylinder 16 may be adjusted at a desired point and not destructively increased, irrespective of what the pressure head may be of the embalming liquid passing through the inlet hose 4. The operator may adjust the screw 14 so as to maintain the working pressure of the fluid within the cylinder 16 at selected working pressure and be informed thereof by the gauge.

This invention has been practically used and has proven exceptionally satisfactory. The invention is defined in the appended claims and is

to be considered comprehensive of all forms of structure coming within their scope.

I claim:

1. In an apparatus of the type described having means for introducing fluid under pressure into a human body, the combination of, means for withdrawing fluid from said human body, and means for maintaining the pressure of the fluid which is being withdrawn above a predetermined 10 pressure.

2. In an embalming system having means to introduce embalming fluid or the like into a body, the combination of, means for preventing said fluid from gravitating out of said body, said last mentioned means comprising a conduit having an opening therein, and means for vertically adjusting said conduit. 80
